VESPER A. SCHLENKER, OF ROCHESTER, NEW YORK

ACOUSTIC DEVICE

Application filed September 20, 1928. Serial No. 307,238.

This invention relates to an acoustic device, such for example, as a mechanism for driving an acoustic diaphragm which may be, for instance, the diaphragm of a radio 5 loud speaker. It has for its principal object the provision of a generally improved mechanism of this character which is more simple and efficient than those heretofore known.

Another object of the invention is the provision of a device of this kind which is more compact than other similar devices previously used.

Still another object is the provision of an acoustic device having a transformer with a 10 comparatively low secondary impedance. Still another object is the provision of mechanism which will operate satisfactorily on a comparatively small input of power.

A further object of the invention is the 15 provision of an acoustic device such as a radio loud speaker which will give purer and more accurate reproduction than other devices previously known.

To these and other ends the invention resides in certain improvements and combinations of parts, all as will be hereinafter more fully described, the novel features being pointed out in the claims at the end of this specification.

30 In the drawings:

Fig. 1 is an elevation of a device constructed in accordance with a preferred embodiment of the invention;

Fig. 2 is a fragmentary section taken substantially on the line 2—2 of Fig. 1;

Fig. 3 is a plan of the mechanism shown in Fig. 1;

Fig. 4 is a view similar to Fig. 3 with parts in section, the section being taken substantially on the line 4—4 of Fig. 1;

Fig. 5 is a vertical section taken substantially through the center of the device;

Fig. 6 is a perspective view of certain electrical conductors used in the device;

Fig. 7 is a diagram illustrating the electrical conductors of the form shown in Figs. 1 to 6, and

Fig. 8 is a perspective view partly in section showing electrical conductors having a somewhat different arrangement for use with

a transformer of a slightly different type. Similar reference numerals throughout the several views indicate the same parts.

The acoustic device of the present application is similar in some respects to that shown in my patent application filed August 6, 1928, Serial No. 297,606. The general principles to be used in the design of a magnet for use in an acoustic device of this kind are set forth at length in said application, and need not be repeated here.

The present device includes, in general, a base 11 on which may be mounted a permanent magnet comprising a bar 12, this bar being secured to the base 11 by the U-shaped member 13 held by screws 14. This bar is bent so as to form a somewhat ring-like member enclosing a substantial area, in order to reduce the leakage flux. The ends of this bar 12 are indicated at 15 in Fig. 2, and to these ends pole pieces 16 are secured by means such as the bolts 17, the pole pieces having a comparatively narrow air-gap between them, as is shown clearly in Figures 2 and 4.

It will be noted that the bar 12 has a cross section, one dimension of which is substantially longer than another dimension. The longer dimension may conveniently be referred to as the width of the magnet, while the shorter dimension may be termed the thickness thereof. For ease of construction as well as for a magnetically efficient magnet, the bar of which the magnet is constructed when bent into a ring-like form should be

bent in the direction of its thickness rather than in the direction of its width. Such a bending, however, ordinarily results in making the longest dimension of the air-gap lie in a direction perpendicular to the plane of the ring of the magnet, and such a construction is illustrated, for example, in my prior

application above referred to.

In an acoustic device of the dynamic type having a conductor vibrating in the air-gap, this conductor would then extend substantially perpendicular to the plane of the magnet ring, and if an acoustic diaphragm were connected to this conductor in the usual manner, the diaphragm would also lie perpendicular to the plane of the ring, thus resulting in a

85

90

95

100

comparatively bulky construction taking up considerable space.

According to the present construction, an arrangement is provided which permits the diaphragm to lie in a plane parallel to the plane of the magnet ring rather than perpendicular thereto, thus resulting in a construction much thinner and more compact than the previous construction above mentioned. 5 This desirable arrangement is accomplished by twisting the ends of the magnet bar 12 in the manner clearly illustrated in Figs. 1 and 3, these ends being twisted through approximately 90 degrees as shown. In this 10 position, the width of the ends lies substantially in the plane of the magnet ring, and the pole pieces 16 attached thereto also lie substantially in this plane, rather than perpendicular thereto. 15 A conductor 20, best shown in Figs. 2 and 5, is mounted to vibrate within the air gap between the pole pieces 16 in response to electric currents flowing through the conductor. This mounting permitting such movement 20 may include arms 21 on the conductor, the ends of these arms being attached to the free ends of resilient plates 22, which plates have their opposite ends fixed. As illustrated in 25 Figs. 1 and 5, six of these resilient plates may be employed, three on one side of the pole pieces 16, and three on the opposite side. The two plates constituting the lower pair when viewed as in Figures 1 and 5 each have their upper edges fixed to cross bars 23, which form 30 part of the electrical circuit, as will be brought out below. The plates 22 of the intermediate pair each have their upper ends secured to cross bars 24 which are insulated from other parts of the device, while the 35 plates of the uppermost pair are secured to the edges of a cross bar 25 which forms part of the electrical circuit. Thus the upper and lower sets of resilient plates 22 constitute 40 electrical connections leading to and from the conductor 20. The mounting of this conductor on the resilient plates is, in general, similar to the construction shown in my prior application above mentioned, and is claimed in said prior application, no claims to this 45 construction per se being made in the present application.

If desired, damping pads 26 of felt or other suitable material may be secured to the resilient supporting and guiding plates 22, and 50 preferably these damping members extend slightly past the edges of the plates, in the manner illustrated in my said prior application.

It will be noted that on account of the twist 55 in the magnet, the conductor 20 lies substantially in the plane of the magnet ring, rather than perpendicular thereto as was the case in my said prior application. This arrangement of the conductor allows the diaphragm 60 to be connected directly and simply to the

conductor, while permitting it to lie in a plane parallel to the plane of the ring, thus producing a desirable compact construction.

In the present instance there is shown a diaphragm 30 having the same general shape as that illustrated in my said prior application, this diaphragm having a ring 31 of U-shaped cross section secured thereto, which ring is connected to the movable conductor 20 by extensions 32 on the conductor. The periphery of the diaphragm 30 may be mounted, for example, on a strip of material 35 having slits 36 (Fig. 1) therein, so that the strip may be curved to conform to the periphery of the diaphragm. The outer edge of this 70 mounting strip 35 may be secured to an angular supporting member 37 as shown in Fig. 5, and a strip 38 of suitable resilient material, such as felt, may extend around this angular 75 diaphragm supporting member and lie 80 against a wall 39 forming part of the cabinet or case in which the device may be placed. The construction of the diaphragm and the manner in which it is attached to and operated by the conductor 20 may be in accordance 85 with the disclosure of my said prior application.

It will be observed from Figs. 4 and 5 that the plane of the periphery of the diaphragm is parallel to the plane of the magnet ring, 90 and that the central portion of the diaphragm projects partly into what might be termed the thickness of the magnet, thus resulting in an unusually compact construction which may be placed within a comparatively thin 95 cabinet or housing. In addition to the feature of compactness, this construction is also advantageous because the magnet itself interferes less with the sound waves produced by the diaphragm than is the case when the plane 100 of the magnet ring is perpendicular to the plane of the periphery of the diaphragm.

In an acoustic device of this type, the best results are obtained when the transformer used in connection with the device has an 105 extremely low secondary impedance, so that it will match as nearly as possible the low impedance of the conductor 20. An important feature of the present invention is the provision of such a transformer, which results in 110 more satisfactory operation and more faithful reproduction than is possible with transformers having a higher impedance.

One possible form of low secondary impedance transformer is illustrated especially 115 in Figs. 1, 5, 6, and 7, and comprises a core having three legs indicated by the numerals 50, 51, and 52. A primary winding 53 surrounds the central leg 50, the ends of this winding being connected to leads 54 (Fig. 1) 120 extending to jacks 55 in which electrical plugs connected to any suitable circuit may be inserted. If desired, one or more intermediate 125 taps may be made in the primary winding. Four leads 54 and jacks 55 are shown in 130

Fig. 1, two of these being connected to the extreme ends of the primary winding 53, while the other two represent intermediate taps.

6 The secondary winding, in the present instance, comprises a plurality of conducting members each of which links only a part of the flux generated by the primary winding 53, these conducting members preferably being connected with each other in parallel, and in series with the air gap conductor 20. For instance, one of these conductors may include a bar or strip 55 extending between the middle leg 50 and the lower leg 52 of the transformer, 10 one end of this strip being connected by a strip 56 with the bar 25 on which the topmost pair of resilient plates 22 is mounted. The opposite end of the strip 55 may be attached to a conducting strip 57 which leads in turn 20 to strips 58 which are connected to the cross pieces 23 on which the lower pair of resilient plates 22 is mounted. Thus the strip 55 links a part of the flux produced by the primary winding 53 (namely that part which flows 25 through the lower leg 52 of the core) and is connected in series with the conductor 20, so that currents induced in this strip 55 will flow through the conductor.

Another part of the secondary winding 30 may include a strip 60 extending through the transformer between the middle leg 50 and the upper leg 51 and being connected at one end to a downwardly extending strip 61, which leads to strips 62 connected to the 35 cross bars 23 which support the resilient plates 22 of the lower pair. The opposite end of this strip 60 is connected to a downwardly extending strip 63 which passes close to the strip 57 but which is insulated therefrom by 40 a layer of insulating material 64. The lower end of this strip 63 is connected to the cross piece 25 which supports the resilient plates 22 of the upper pair.

It will be seen that the strips 60, 61 and 63 45 constitute a secondary winding linking a part of the flux produced by the primary winding, this part being equivalent to that proportion of the flux which passes through the upper leg 51 of the transformer. This portion 50 of the secondary winding is connected in series with the air gap conductor 20, as will be observed, and in parallel with the other portion 55 of the secondary winding.

Since each of the two portions 55 and 60 of 55 the secondary winding link half of the flux produced by the primary winding, and since these two portions are connected in parallel rather than in series, it follows that as far as the impedance ratio is concerned, the transformer is equivalent to one of the conventional type having a primary of the same number of turns as is here used and having a secondary winding of only half a turn. By using a transformer of this kind in an acoustic device of this nature, the primary can be

made of proper size to match as near as possible the impedance of the tube to which the primary is connected, while the secondary can be made to match satisfactorily the extremely low impedance of the conductor 20, thus resulting in superior reproduction and requiring only a comparatively small power input.

The strips 55 and 60 of the secondary winding are, of course, insulated from the transformer core by any suitable means, such as the 70 layers 66 of insulating material. The cross bars 24 which support the resilient plates 22 of the middle pair form no part of the electrical circuit, and are insulated from the pole pieces 16 and from the conducting strips 58 75 and 62 by various layers of insulation and insulating bushings, as is plainly shown in Fig. 2.

A low secondary impedance transformer of another type which is suitable for use in the 80 present apparatus is illustrated in Fig. 8. In this construction, the transformer core is of rectangular form, and is subdivided into a plurality of separate sections lying side by side, three sections 71, 72, and 73 being illustrated. Blocks 74 of insulating material are inserted between the sections of the core and act as spacers to keep them apart, as is plainly shown. A primary winding 75 extends around all three of the core sections. The 85 secondary winding comprises a plurality of conducting members each linking a part only of the flux generated by the primary winding, these conducting members being connected with each other in parallel and in series 90 with the vibrating conductor in the air gap.

In the construction illustrated by way of example in Fig. 8, the secondary winding comprises three U-shaped strips each having a long leg 76 and a shorter leg 77, each of 105 these U-shaped strips extending around one of the sections of the transformer core as is clearly illustrated, so that each strip links a part only of the flux in the whole core. The long legs 76 of the three U-shaped members 110 may be connected to each other by a plate 78, while the shorter legs 77 may likewise be connected to each other by rods 79 which extend through openings in the legs 76 so that they do not come into electrical contact therewith.

Thus the three sections of the secondary winding are connected to each other in parallel, and they may be connected in series with the vibrating conductor 20 by suitable leads 120 80. It will be understood, of course, that the transformer core may be split into any suitable number of sections, three of these being shown simply by way of example. A construction of the type illustrated is equivalent 125 from an impedance standpoint to a conventional transformer having a primary of the same number of turns shown and having a secondary winding of only one-third of a turn. Obviously the transformer core could 130

be split into any number of sections desired. If four sections were used, the secondary winding would be equivalent to a quarter of a turn, while if five sections were used, it 5 would be equivalent to a fifth of a turn. Thus the number of sections in the transformer core can be varied in order to obtain a transformer having a primary winding of the required impedance to match that of the tube, 10 while the secondary impedance may match that of the moving conductor 20.

It will be understood, of course, by those skilled in the art that any suitable source of audio-frequency electrical waves may be connected to the primary winding of either of the 15 transformers disclosed above, in which case the diaphragm 30 will be caused to vibrate in accordance with the audio-frequency waves. If desired, the operation of the apparatus may be reversed, sound waves falling 20 upon the diaphragm 30 being caused to vibrate this diaphragm and to move the conductor 20, thus producing corresponding electrical impulses in the primary winding. 25 Likewise, a phonograph stylus can be attached to the conductor 20, and made to vibrate the same, so that the device may be employed for a phonograph pick-up.

Any suitable framework may be used for 30 supporting the various parts of the apparatus. A convenient arrangement, as shown particularly in Figs. 1, 3, and 5, includes upright angle bars 85 having horizontal extensions 86 and 87 at their upper and lower 35 ends respectively, the ends of these horizontal extensions being secured by means such as screws 88 to the angular frame 37 which extends around the periphery of the diaphragm. The transformer may be supported 40 by the members 85 and 86. The bolts 17 which attach the pole pieces to the magnet bar 12 extend through the upright angle members 85, as shown in Figs. 1 and 2. Preferably three bolts are used to attach each 45 pole piece 16 to the magnet bar, and if desired, only the upper and lower bolts may extend through the angle bars 85, the middle bolts being received in recesses 89 formed in these angle bars as shown in Fig. 4. This 50 permits each pole piece 16 to be bolted conveniently to the magnet bar 12 by means of the middle bolt 17, and the frame members 85 may later be assembled on the pole pieces and secured to them and to the magnet bar 12 by 55 the upper and lower bolts 17.

While certain embodiments of the invention have been disclosed, it is to be understood that the inventive idea may be carried 60 out in a number of ways. This application is therefore not to be limited to the precise details shown, but is intended to cover all variations and modifications thereof falling within the spirit of the invention, or the 65 scope of the appended claims.

I claim as my invention:

1. An acoustic device comprising a magnet having an air gap, a conductor mounted for movement within the air gap, a transformer having a flux-generating winding, and a conducting member linking a part only of the flux generated by said winding, said conducting member being electrically connected to the conductor in the air gap. 70

2. An acoustic device comprising a magnet having an air gap, a conductor mounted for movement within the air gap, a transformer having a flux-generating winding, a conducting member linking a part only of the flux generated by said winding, and a second conducting member linking another part of said flux, said two conducting members being connected in parallel with each other and in series with the conductor in the air gap. 75

3. An acoustic device comprising a magnet having an air gap, a conductor mounted for movement within the air gap, a transformer having a flux-generating winding, and a plurality of conducting members each linking a part only of the flux generated by said winding, said conducting members being connected in parallel with each other and being electrically connected to the conductor in the air gap. 80

4. A radio loud speaker comprising, in combination, a magnet having an air gap, a conductor mounted for movement within said air gap in response to electric currents flowing through said conductor, an acoustic diaphragm connected to said conductor to be moved thereby, and a low secondary impedance transformer including a flux-generating primary winding and a secondary winding comprising a plurality of conducting members each linking a part only of the flux generated by said primary winding, said conducting members being connected in parallel with each other and in series with the conductor in the air gap, whereby said diaphragm will be vibrated in accordance with electric currents impressed upon said primary winding. 90

5. A radio loud speaker comprising a magnet formed of a bar bent into a ring-like shape and having an air gap, a conductor mounted for movement within said air gap in response to electric currents flowing through said conductor, said conductor lying substantially in the plane of the ring, and an acoustic diaphragm connected to the conductor to be moved thereby, the periphery of said diaphragm lying substantially in a plane parallel to the plane of the ring, whereby to provide a comparatively thin and compact device. 100

6. An acoustic device for transforming electric waves into sound waves or vice versa, comprising in combination a magnet having an air gap, a conductor mounted for movement within said air gap, an acoustic dia- 105

phragm operatively connected to said conductor for movement therewith, a transformer core divided into a plurality of sections, a primary winding encircling all of said sections, and a secondary winding comprising a plurality of conducting members each encircling only one of said sections and being connected in parallel with each other and in series with the conductor in the air gap, to provide a secondary winding of low impedance substantially matching the impedance of said conductor.

7. An acoustic device for transforming electric waves into sound waves or vice versa, comprising in combination a magnet having an air gap, a conductor mounted for movement within said air gap, an acoustic diaphragm operatively connected to said conductor for movement therewith, a transformer core having a plurality of winding legs including at least two legs through which only a part of the flux passes, a primary winding for producing flux in said legs, and a secondary winding comprising a plurality of conducting members each encircling only one of said legs through which only part of the flux passes, said conducting members being connected in parallel with each other and in series with the conductor in the air gap, to provide a secondary winding of low impedance substantially matching the impedance of said conductor.

8. A radio loud speaker comprising a magnet formed of a bar substantially wider than its thickness, said bar being bent into a ring-like shape having an air gap therein, the intermediate portion of said bar having its width substantially perpendicular to the plane of the ring, the ends of said bar adjacent the air gap being twisted so that at the air gap the width of said bar lies substantially in the plane of the ring, a conductor lying substantially in the plane of the ring and mounted for movement within said air gap in response to electric currents flowing through said conductor, and a relatively large direct-acting acoustic diaphragm operatively connected to said conductor to be moved thereby, the periphery of said diaphragm lying substantially in a plane parallel to the plane of the ring to provide a comparatively thin and compact device.

VESPER A. SCHLENKER.
